ELECTRICAL MUSICAL INSTRUMENT

John M. Hanert, Park Ridge, Ill., assignor to
 Hammond Instrument Company, Chicago, Ill.,
 a corporation of Delaware

Application February 16, 1948, Serial No. 8,680

7 Claims. (Cl. 84—1.24)

1

My invention relates generally to electrical musical instruments and more particularly to improved key-operated control circuits for such instruments.

In electrical musical instruments played in non-reverberative rooms, it is desirable that the tones produced have a gradual decay after the release of the key, thereby to produce the equivalent of the reverberation effect. Since it is the depression of the key which necessarily determines the pitch of the tone to be sounded, the release of the key leaves indeterminate the pitch of the decay portion of the tone unless there is incorporated some mechanism or circuit in the instrument which is capable of "remembering" the last key depressed until another key is depressed. While this may be accomplished mechanically by the use of various types of latch and bail mechanisms, such mechanisms usually require the use of a large number of parts which must be made with precision and are thus costly, are subject to wear, and may become noisy in operation.

It is thus a primary object of my invention to provide improved means for controlling an electrical musical instrument to secure the reverberation effect by causing the tones produced to decay gradually after the release of the key which was depressed to cause the tone to sound.

A further object is to provide an improved key-controlled circuit for an electrical musical instrument which has means for causing a tone to be sounded for a predetermined time after the release of the key.

A further object is to provide an improved electrical musical instrument in which relays are employed in the key circuits and in which each of the relays is provided with a holding circuit and is adapted to control the pitch of the tone produced.

Other objects will appear from the following description, reference being had to the accompanying drawing in which:

Figure 1 is a schematic wiring diagram of an exemplary form of the invention;

Figures 2, 3 and 4 are similar diagrams of modified forms of the invention.

For purposes of illustration the invention will be described as incorporated in an instrument of the melody type, that is, one which is capable of playing but a single note at one time and is provided with a generating system for producing the notes of the pedal register of an organ, or for use as a piano accompaniment instrument of the type shown in my prior Patent No. 2,357,191.

2

The instrument comprises a plurality of pedals CO to C1 for the control of tones having fundamental frequencies of 32,703 to 65,406 C. P.S. All the keys except C1 are arranged upon depression to close a switch A and open a switch B, the key C1 operating to close a switch A only. Each of the switches A (except the switch A for key CO) is adapted upon closure to complete a circuit through a winding of a relay 10, which, upon being energized, closes a switch C and opens a switch D.

Energization of the relays is accomplished through a circuit including a source of potential indicated as a terminal +24 v. connected to a conductor 12 through a relay winding 14. Upon closure of a switch A (except for key CO) a circuit is completed to a relay 10 which has one grounded terminal. Upon energization of the relay 10 its switch C closes to complete a holding circuit which connects the ungrounded terminal of the winding of relay 10 through this switch C and the series of switches B associated with all keys of lower pitch, the circuit being thus completed to the +24 v. terminal.

It will be apparent from the circuit diagram that as a result of the completion of the relay holding circuits through the switches B of lower keys, that depression of any key lower than that previously depressed will open the holding circuit of the previously depressed key, whereas depression of a key higher than the previously depressed key will not unlock the holding circuit established by the previously depressed key.

The switches D are connected in series, the highest key C1 having its switch D connected to ground. The junctions intermediate the switches D are connected to a conductor 16 through parallel capacitors C18. Thus, depending upon which of the relays 10 is energized none, or any other number, or all of the capacitors C18 will be connected in parallel between the conductor 16 and ground and will thus be in parallel with a capacitor C20 which forms part of a parallel resonant mesh including a variable tuning inductance L22, the latter being coupled to a feedback inductance L24. The conductor 16 is connected through a grid leak resistor R26 and a capacitor C28 with the grid 30 of pentode 32, the cathode and suppressor grid of which are connected to ground through the inductance L24. Operating potentials are supplied to the screen grid and plate of the pentode 32 from a suitable source of potential indicated as a terminal +B through a voltage dropping resistor R36 and a load resistor R38 respectively. The screen grid is connected to

ground through a filtering capacitor C39. The pentode 32 with its associated circuits thus comprises an oscillator, the frequency of operation of which is determined by the number of capacitors C18 which are connected in parallel with its capacitor C20. The oscillator is initially tuned by adjustment of variable inductance L22.

The output of the oscillator pentode 32 is coupled to suitable tone controls 40 through a blocking capacitor C42. The tone controls may comprise any suitable types of selectively coupled resonant circuits having different frequency response characteristics and controllable by selectively operable switches, such as shown, for example, in my prior Patent No. 2,276,390. The signal, as modified by the tone controls, is impressed upon the control grid of a phase splitting triode 44 having its cathode connected to ground through series resistors R46 and R47. The junction of these two resistors is connected to the control grid through a grid resistor R48. Plate voltage is supplied through a load resistor R50 connected to a suitable source of potential indicated as +B, and the plate is coupled to the control grid of a control pentode 52 through a blocking capacitor C54.

In a similar manner the junction between the resistors R46 and R47 is connected to the control grid of a control tube 53 through a blocking capacitor C55. The suppressor grids of the pentodes 52 and 53 are connected to their cathodes while the screen grids are connected together and have a suitable operating potential impressed thereon through voltage dividing resistors R60, R61 and variable volume control resistor R62 connected between a +B terminal and ground. The cathodes of these pentodes are connected to ground and are connected to a junction point 64 through a decay capacitor C66, which may have a capacitor C68 connected in parallel therewith upon closure of a manually operable switch 70. The terminal 64 is connected to the control grids of pentodes 52 and 53 through grid resistors R72 and R73 respectively, and a negative cut-off bias is normally supplied to the grids through R74 which is connected between the terminal 64 and a suitable cut-off biasing potential source indicated as a terminal -60 v. The terminal 64 is connected through a resistor R76 and conductor 78 to one pole of a switch 80 forming part of relay 14, the other pole of the switch 80 being connected to ground.

In view of the fact that the key CO does not have a relay 10 associated therewith, its switch A is adapted to connect a suitable compensating load resistor R82 between conductor 12 and ground when the switch is closed, the resistance of R82 being comparable to that of the winding of a relay 10.

The relays 10 and 14 preferably have anti-spark resistors (not shown) connected in parallel therewith to prevent excessive sparking at the contacts of switches A.

The pentodes 52 and 53 are supplied with plate voltage from a terminal +B through load resistors R84 and R85 and the output of these pentodes is coupled to the input of a push-pull amplifier 86 through blocking condensers C38 and C39 respectively. A speaker 90 is coupled to the output of the power amplifier 86.

From the foregoing it will appear that when any one of the keys CO# to C1 is depressed the closure of switch A will result in the energization of its associated relay 10 and the opening of the switch B will cut off the supply of energizing

current to all relays 10 associated with keys higher in the musical scale. The closure of the switch A will also result in energization of relay 14 with the resultant closure of switch 80, thereby connecting terminal 64 to ground through resistor R76. The resistors R74 and R76 thus form a voltage divider, determining the potential on the terminal 64. The potential on this terminal will therefoer rise gradually as the capacitor C66 is discharged, and the gain of the pentodes 52 and 53 will therefore increase gradually from below cutoff to a substantial value sufficient to transmit the signal at maximum amplitude. The rate of attack will of course depend upon the relative values of R76, R74 and C66 (also C68 if switch 70 is closed) and the tone will thus be produced by the speaker 90 at gradually increasing intensity, the maximum value of which may be controlled by the volume control variable resistor R62.

Upon energization of the relay 10 associated with the depressed key its switch C closes and switch D opens. Closing of the switch C establishes the holding circuit previously described, while the opening of the switch D determines the number of capacitor C18 which are in parallel with the capacitor C20 in the tuning circuit of the oscillator pentode 32. The values of the capacitors C18 are so chosen so that the oscillator will oscillate at a frequency corresponding to the pitch of the depressed key.

Upon release of the depressed key the relay 14 is deenergized, opening the switch 80 and permitting the potential of terminal 64 to drift gradually to its cut-off bias potential of -60 volts, the rate at which this is accomplished depending mainly upon the relative values of R14 and C66 (and C68 if switch 70 is closed). The relay 10 associated with the depressed key will however be maintained in energized condition until another key is subsequently depressed. If the second key depressed is of higher pitch than the first depressed key the relay associated with the first depressed key will remain energized. Thus, for example, if the keys CO# to C1 were depressed in succession, all of the relays 10 would eventually be locked in an energized state.

By virtue of the fact that this is a possibility it is necessary that the source of current for the operation of these relays be adequate to permit this to take place. On the other hand, if the keys are successively depressed commencing with the key C1 and ending with the key CO, the depression of each key will open the holding circuit for the relay of the prior depressed key and thus the load on the +24 v. current source will be limited to that required for the energization of but one of the relays at any one time. In playing a musical composition it will be seldom that more than three or four of the relays 10 will be simultaneously energized.

The switches D are intended to be representative of any switch in any musical instrument which controls the selection of the pitch to be sounded. For example, the switches D, instead of being opened upon the energization of their associated relays, might be arranged to be closed thereby, and the switches might then be arranged to effect the selective energization of solenoid-operated valves controlling the wind supply to organ pipes. They might also be used to connect electrical generators (e. g. of the type shown in Hammond Patent 1,956,350) to a suitable output circuit, or to control the energization of other types of electrical tone signal gen-

erators. In utilizing the key control circuits of the invention with the pipe organ and other instruments it may not be necessary to provide the relay 14. Instead the conductor 12 might be connected directly to the operating potential source +24 v.

The invention is of greatest utility when employed in connection with the bass register tones of an instrument since the reverberation effect is not as essential in the production of treble register tones. In the bass register a long decay of the tones will produce the effect of a long reverberation time. The duration of the decay time may be suited to the enclosure in which the instrument is to be played by proper selection of the values of C66, C68 and R74.

In the circuit shown in Fig. 1 the highest of a plurality of simultaneously depressed keys determines the frequency to which the oscillator is tuned. In some instances it may be preferred to have the lowest of several simultaneously depressed keys determine the frequency generated. The latter result may be accomplished by the circuit shown in Fig. 2.

In Fig. 2, each of the keys CO to C1, upon depression, closes a switch 101, and in addition each of the keys CO# to C1 opens a switch 102. Closure of a switch 101 associated with keys CO to BO connects a conductor 103 to ground through a relay winding 104 associated with the depressed key, while closure of switch 101 associated with key C1 connects conductor 103 to ground through a compensating resistor R105. The conductor 103 is connected to a suitable source of current, indicated as a +24 v. terminal, through a relay winding 108.

Each of the relays 104 is adapted, upon energization, to close a switch 110 to complete a holding circuit. It will be noted that the holding circuit for each of the relays 104 includes in series the switches 102 for all of the higher pitch keys, and will therefore be broken upon depression of any higher key.

Each of relays 104, upon energization, also closes a switch 112, effective to tune the oscillator to the pitch corresponding to the lowest of several simultaneously depressed keys. Each of the switches 112 has one pole connected to ground and the other pole connected to one of a series of junction points between a series of capacitors C114. The last capacitor C114 of the series is connected to ground so that the series is effectively in parallel with capacitor C20 and variable inductance L22. These capacitors, together with the inductance L22 form the resonant tuning circuit of an oscillator similar to that described with reference to Fig. 1. The same reference characters have therefore been applied to the corresponding parts of the two oscillators.

The oscillator of Fig. 2 has its output coupled to an output system 116 similar to that shown in greater detail in Fig. 1, and the signals from this output system are translated into sound by a speaker 118. The relay 108 operates a switch 120 (corresponding to switch 80 of Fig. 1) to control the attack and decay of the tone signals transmitted by the output system 116.

The instrument shown in Fig. 2 operates in substantially the same manner as that shown in Fig. 1 except that in the apparatus of Fig. 2 the lowest of several simultaneously depressed keys or pedals determines the pitch of the tone produced. If a number of notes are played commencing at the high end of the scale, the relay associated with the higher key will remain in

locked condition after such key is released, but on the other hand, if a series of keys are played, commencing at the lower end of the scale, each higher key upon its depression will open the circuit supplying energizing current for all the relays 104 associated with the lower keys.

The modified forms of the invention shown in the Figs. 3 and 4 have many parts identical with or similar to those previously described and the same reference characters have therefore been applied to corresponding parts.

In Fig. 3, the relays 10 are operated in the same manner as in Fig. 1. Each relay, upon being energized, closes its switch C and moves its double throw switch 130 from its full line position to its dotted line position. The switches 130 are connected in series when in full line position, and when moved to dotted line position make connection with one of the output terminals of a tone frequency generator 132, which may be of the phonic wheel type, as shown in the patent to Laurens Hammond No. 1,956,350. The generator 132 may also be an electronic oscillator, a vibratory reed with electric pickup, or of any other suitable type, preferably generating a complex wave. The switch 130 for the note C1 is connected to an amplifier 134 which may include tone, attack, decay, and volume controls, the output of the amplifier being fed to a speaker 136.

From the foregoing, it will be clear that the highest of a plurality of depressed keys will, through operation of its associated switch 130, connect its generator 132 to the amplifier and also open the circuit between the amplifier 134 and all of the generators 132 associated with lower keys. It will thus be seen that the generator 132 associated with the highest of a plurality of keys depressed will be effective to transmit the musical tone signal generated thereby to the amplifier.

As in the previously described embodiments, the switch 80 will be closed upon depression of any of the keys and will cause the amplifier to transmit the signal with the desired attack, and upon release of the keys, the switch 80 will open and the gain of the amplifier will decrease at a predetermined rate to provide the desired decay. It will be noted however, that the highest energized relay 10 will remain locked so that its associated generator will continue to supply the tone signal to the amplifier throughout this decay period.

In the embodiment of the invention shown in Fig. 4, the relay operated switches D are connected to control the supply of energizing current to the plates of vacuum tube oscillators. The relay operated switch 80, when closed, connects a source of plate current indicated as B+

60 to a conductor 140 which is connected to one pole of the switch 130 associated with the relay 10 of the highest key C1. The switches 130, when in full line positions, connect the conductor 140 to a resistor R142 associated with an oscillator 144 of the lowest key CO. A resistor R146 is connected between the resistor R142 and the plate of a triode 148, a capacitor C150 being connected between the junction of the resistors R142-R146 and ground. The oscillator 144

65 comprises an inductance L152 which has one terminal connected to the grid of the triode 148 through a grid bias resistor R154 and a bypass capacitor C156, the other terminal of the inductance L152 being connected to ground. A capacitor C158 is connected in parallel with the

inductance L_{152} , and the cathode of the triode 148 is connected to a tap 160 on the inductance L_{152} .

The output of the oscillator 144 is transmitted to an amplifier 162 through a blocking capacitor C_{164} and a resistor R_{166} . The amplifier 162 may include the usual tone quality and volume controls and has its output connected to a speaker 165 . The switch 80 is provided with a dashpot 166 which permits the switch 80 to close rapidly but delays the opening of the switch after its relay winding 14 has been deenergized, for an interval in the order of 1.5 seconds.

From the foregoing it will appear that whenever one of the keys is depressed, its associated relay 10 will be energized and the switch C of this energized relay will close to establish a holding circuit. Also the switch D of the energized relay 10 will be moved from full to dotted line position and thereby supply plate current to the associated oscillator and cause the latter to commence oscillating. The capacitors C_{150} , together with their associated resistors R_{142} and R_{146} , operate as filters to reduce transients which may be caused by the closure of the switches D . It will be understood that there is an oscillator, such as 144 , associated with each of the playing keys and that the outputs of these oscillators are connected in parallel to the amplifier 162 . These oscillators are intended to be representative of any musical tone generator, electrical or mechanical, the operation of which may be controlled by the completion of a circuit supplying electrical energy thereto. For example, electro-magnetically operated valves controlling the supply of wind to organ pipes may be substituted for the oscillators.

In playing any of the instruments disclosed the player may, without any attention upon his part, merely by depressing the pedals or keys in a staccato manner, cause the tones to persist through the desired decay period and thus produce a desirable reverberation effect. If the keys are depressed in a legato manner, the tones will have the usual intensity envelopes of sustained organ tones. Since, in the forms of the invention shown in Figs. 1, 2, and 3, the amplifier is cut off when no keys are depressed, the depression of a key or pedal does not, as a result of the closure of its switch D , 130 , or 112 , produce any undesirable transients in the signal supplied to the speaker, and thus key clicks or thumps are not present in the tone produced.

While I have shown and described particular embodiments of my invention, it will be apparent to those skilled in the art that numerous modifications and variations may be made in the form and construction thereof, without departing from the more fundamental principles of the invention. I therefore desire, by the following claims, to include within the scope of my invention all such similar and modified forms of the apparatus disclosed, by which substantially the results of the invention may be obtained by substantially the same or equivalent means.

I claim:

1. In an electrical musical instrument having electrical musical tone signal generating means, a plurality of playing keys; a relay associated with each of said keys; a circuit for each of the keys including a switch operated by the key, the winding of its associated relay and a source of energy in series; a holding circuit for each of said relays, each holding circuit including in series a switch operated by the relay, a source

of energy, and switches opened respectively by operation of keys for notes lower in the musical scale; switches operable by the relays respectively to determine the pitch of the tone signal provided by the generating means; and an output system including an amplifier and electroacoustic translating means, said amplifier having means to control its gain in response to depression of any of said keys thereby to cause the sounding of a tone with gradual attack.

2. In an electrical musical instrument having an output system including an amplifier electroacoustic translating means, an electrical musical tone signal generating means capable of providing signals of the frequencies of the notes of the musical scale, and a plurality of playing keys; the combination of a switch A associated with each key and closed upon depression thereof, a switch B , associated with each key and opened upon depression thereof; a relay associated with each of the keys; a source of electrical energy; an energizing circuit for each relay including in series the switch A , the relay winding, and the source; a pair of switches C and D respectively closed and opened upon energization of the relay; a holding circuit for each relay including in series the relay winding, the source, and all of the switches B associated with keys of lower pitch; means responsive to the operation of switch D to cause the generating means to supply to the output system a signal of frequency corresponding to the pitch of the depressed key; and means associated with the amplifier and controlled in common by all of the keys to render said amplifier ineffective to transmit signals when none of the keys is depressed and to cause the amplifier to transmit the signal with gradual attack upon depression of any key and with gradual decay upon release of the key.
3. In an electrical musical instrument of the melody type having an amplifier including a terminal, the potential of which determines its gain, an electroacoustic translating means coupled to the amplifier output, and a tunable oscillator coupled to the input of the amplifier; the combination of a keyboard comprising a plurality of playing keys, a pair of switches A and B associated respectively with each of said keys, switches A being closed and switches B being opened upon depression of the associated key; a key relay associated with each key, each key relay including switches C and D , switch C being closed when the relay is energized; a control relay operating a switch 80 when energized; a mesh including switch 80 and connected to the said terminal of the amplifier to cause the potential on the terminal to change in a direction to cause gradual increase in the gain of the amplifier when the switch is closed and to cause the potential on the terminal to change gradually in the opposite direction when the switch is opened; a circuit including in series a source of energy, the winding of the control relay, and said switches A in parallel; means controlled by the switches D to tune the oscillator to the various musical tone frequencies; and a holding circuit for each of the key relays, each of the holding circuits including all the switches B associated with keys nearer one end of the keyboard than the key with which the particular relay is associated.
4. In an electrical musical instrument having electrical tone signal generating means; a keyboard comprising a plurality of playing keys; a relay associated with each key; a circuit for each of the keys including in series a switch operated

by the key, the winding of its associated relay, and a source of energy; a holding circuit for each of the relays, each holding circuit including in series a source of energy, a switch closed by the relay, and switches opened respectively by the depression of keys nearer one end of the keyboard than the key with which the relay is associated; switches operated respectively by the relays, the switch of the relay associated with the key farthest from said end of the keyboard being effective to determine the pitch of the tone signal provided by the generating means; and an output system for amplifying the tone signals provided by the generating means and translating the amplified signals into sound.

5. The combination set forth in claim 4 in which there is provided an additional relay energized upon the operation of any of the keys, and in which this relay controls the intensity envelope of the tones produced by the translating means.

6. In a musical instrument having musical tone producing means; a keyboard comprising a plurality of playing keys; a relay associated with each key; a circuit for each of the keys including, in series, a switch operated by the key, the wind-

10
5 ing of its associated relay, and a source of energy; a holding circuit for each of the relays, each holding circuit including in series a source of energy, a switch closed by the relay, and switches opened respectively by the depression of keys nearer one end of the keyboard than the key with which the relay is associated; and additional switches operated respectively by the relays, and means controlled by the additional switches to cause the tone producing means to produce a tone of a pitch corresponding to that of the key by which it is controlled and when a plurality of keys are operated at the same time to produce a tone of the pitch corresponding to that one of the operated keys which is farthest from said end of the keyboard.

15
10 20 7. The combination set forth in claim 6 in which there is provided an additional relay energized upon the operation of any of the keys, and in which this relay controls the intensity envelope of the tones emitted by the tone producing means.

JOHN M. HANERT.
